UNITED STATES PATENT OFFICE.

WILLIAM R. LEE, OF ROCHESTER, NEW YORK.

PACKAGING PIPE-CLEANERS.

1,108,450.

Specification of Letters Patent. Patented Aug. 25, 1914.

Application filed August 6, 1912. Serial No. 713,575.

To all whom it may concern:

Be it known that I, WILLIAM R. LEE, of Rochester, in the county of Monroe and State of New York, have invented a new and useful Improvement in Packaging Pipe-Cleaners, which improvement is fully set forth in the following specification and shown in the accompanying drawings.

The present invention relates to the packaging of pipe cleaners and an object of the same is to provide a compact package which will contain a bundle of pipe stem cleaners and a pipe bowl cleaner.

Another object of the invention is to provide a pipe bowl cleaner adapted to be contained within a small package and preferably having provision for holding together a bundle of pipe stem cleaners.

A further object of the invention is to provide a package in which a bowl cleaner will be so connected to the stem cleaners that it will not become accidentally disconnected therefrom.

To these and other ends the invention consists in certain parts and combinations of parts all of which will be hereinafter described, the novel features being pointed out in the appended claims.

In the drawings: Figures 1 and 2 are respectively two views at right angles to each other of one embodiment of the invention; Figs. 3 and 4 are similar views of another embodiment of the invention; and Figs. 5 and 6 are similar views of still another embodiment of the invention.

The package preferably comprises a plurality or bundle of pipe stem cleaners 1 formed in this instance of strands of wire covered with fibrous material and held together by a suitable wrapper 2 of paper or the like. Combined with this bundle of stem cleaners is a bowl cleaner comprising preferably a blade portion 3 having a suitable hand piece at one end, all of which may be formed from one piece of sheet metal. In the embodiment of the invention shown in Figs. 1 and 2, the hand piece comprises a substantially U-shaped and laterally deflected portion 4 having its arms provided with two perforations or openings through which the bundle of pipe stem cleaners is passed in the manner shown in Figs. 1 and 2. In the embodiment shown in Figs. 3 and 4, the hand piece is in the form of a laterally deflected arm portion 4^a provided with a perforation having the bundle

of stems passed therethrough. In the embodiment shown in Figs. 5 and 6, the hand piece 4^b is only deflected laterally a slight distance and is provided with a small opening to receive one of the pipe stem cleaners 1.

In all illustrated embodiments of the invention, the blade 3 of the pipe stem cleaner is introduced into one end of the wrapper sleeve 2 so as to extend in the direction of the length of the bundle, while the hand piece of the pipe bowl cleaner surrounds one or more of the pipe stem cleaners 1. This arrangement tends to hold the pipe bowl cleaner within the sleeve 2 and, as the latter is made of paper, prevents the pipe bowl cleaner from tearing the sleeve in transportation. Furthermore, when the pipe bowl cleaners entirely surrounds the pipe stem cleaners, it holds the latter in compact form and prevents the accidental tearing of the sleeve 2 by one of the pipe stem cleaners being pulled laterally. The embodiment shown in Figs. 1 and 2 has the further advantage that it will provide a complete securing means for the pipe stem cleaners, as the wrapper, with this construction, may be eliminated.

What I claim as my invention and desire to secure by Letters Patent is:

1. A package of pipe cleaners comprising a bundle of stem cleaners, a wrapper passed about the stem cleaners, and a bowl cleaner provided with a blade fitting in said wrapper and having a hand piece deflected laterally with relation to the blade and formed with an opening through which at least one of the cleaners is passed.

2. A package of pipe cleaners comprising a bundle of stem cleaners and a bowl cleaner having a portion surrounding the stem cleaners.

3. A package of pipe cleaners comprising a bundle of stem cleaners and a bowl cleaner having a blade extending in the direction of the length of the bundle and a hand piece surrounding the entire bundle.

4. A package of pipe cleaners comprising a bundle of stem cleaners and a bowl cleaner provided with a blade and a hand piece, the latter having a substantially U-shaped portion formed with two openings through which the stem cleaners are passed.

WILLIAM R. LEE.
